(57) **CLAIM**

We claim the ornamental design for the utility hub, as shown and described.

DESCRIPTION

FIG. 1 is a perspective view of the front, top and side of the utility hub of the present invention;

FIG. 2 is an elevational view of the front of the utility hub of the present invention;

FIG. 3 is an elevational view of the first side of the utility hub of the present invention;

FIG. 4 is an elevational view of the rear of the utility hub of the present invention;

FIG. 5 is a plan view of the top of the utility hub of the present invention; and,

FIG. 6 is a plan view of the bottom of the utility hub of the present invention.

The first side elevational view shown in FIG. 3 is a mirror image of the opposite side of the utility hub of the present invention.

The broken line environmental showing is for illustrative purposes only and forms no part of the claimed design.
